DESIGN FOR A SHOWER HEAD

Harry Landgarten, Brooklyn, N. Y.

Application March 12, 1938, Serial No. 75,781

Term of patent 7 years

To all whom it may concern:

Be it known that I, Harry Landgarten, a citizen of the United States, residing in the Borough of Brooklyn, in the county of Kings, city and State of New York, have invented a new, original, and ornamental Design for a Shower Head, of which the following is a specification, reference being had to the accompanying drawing, forming part thereof.

Fig. 1 is a perspective view of a shower head, showing my new design.

Fig. 2 is a bottom plan view of the same.

Fig. 3 is an elevational view of the same.

I claim:

The ornamental design for a shower head, as shown.

HARRY LANDGARTEN.
